UNITED STATES PATENT OFFICE.

WARREN M. OSBORN, OF CHICAGO, ILLINOIS, ASSIGNOR TO CHICAGO MALLEABLE CASTINGS COMPANY, OF CHICAGO, ILLINOIS, A CORPORATION OF ILLINOIS.

RAIL-ANCHORING DEVICE.

1,413,055.

Specification of Letters Patent. Patented Apr. 18, 1922.

Application filed August 18, 1921. Serial No. 493,224.

To all whom it may concern:

Be it known that I, WARREN M. OSBORN, a citizen of the United States, residing at Chicago, in the county of Cook, State of Illinois, having invented certain new and useful Improvements in Rail-Anchoring Devices, do hereby declare that the following is a full, clear, and exact description of the same.

10 My invention relates to improvements in devices for anchoring railway rails, and its main object is to provide a clip that will interlock the rail and tie plate, and also receive the spikes which hold the plate upon 15 the tie; other objects and features will be apparent from the disclosure.

The invention consists in the matters hereinafter described and then pointed out in the claims.

20 In the accompanying drawing, Fig. 1 is a perspective view showing a pair of the clips in place on an assembled plate and rail; Fig. 2 is a view in cross section on the line 2—2 of Fig. 1 showing the device in 25 position on the tie, and Fig. 3 is a detail perspective view of one of the clips.

In the drawing the reference letter A represents the head of a rail, B its base, and C the web uniting the head and base.

30 The plate consists of the usual body 1 provided near each side with transversely elongated spike holes 2 to receive the usual spikes 3 which are driven into the underlying tie 4.

The clips, designated generally by the 35 reference letter D, are of metal having a substantially rectangular body and provided at their inner edges with shoulders 5 to abut the rail-base and with flanges 6 to overlie the base. The lower sides or faces are provided with downwardly projecting lugs 7 whose inner faces are substantially in the same vertical plane as the shoulders 5 and whose lower ends are provided with inwardly directed wings 8; the flanges 6 and 40 wings 8 are substantially parallel, the former being slightly beveled to fit the inclined top of the rail-base, and form a pocket or seat for the edges of the base B and plate 1. The ends of the lugs 7 are beveled 45 or inclined longitudinally from their centers toward their sides to form longitudinal tie-engaging ribs or edges 9 which extend parallel with the bodies of the lugs and so transverse to the creeping stresses or strains

of the rails under traffic conditions; the ends 55 of the lugs are also beveled in each direction from an intermediate point toward the ends to form transverse tie-engaging ribs or edges 10 which resist the cross-strains or thrusts on the rails. The two series of ribs 60 cross to form a projecting point 11 to engage the tie. The clips are provided with spike-holes 12 arranged outside or in the rear of the lugs 7, and preferably with spike-heeling lugs 13 arranged in the rear of the 65 spike-holes and with their inner faces in extension of the outer walls of these holes. When the heeling lugs are used they are provided with inclined or beveled upper ends as shown to crowd or wedge the spike 70 inwardly; they also prevent throat-cutting of the neck-portions of the spikes by the clips or plates. The outer ends of the clips are provided with heels 14 which prevent their tilting and hold them in position 75 against the rail-base. The upper faces of the clips are made slightly concave in front of their spike-holes 12 and also on each side of these spike-holes and the heeling-lugs as indicated at 15 in Fig. 2; this forms a transverse rib 16 of approximately the same 80 height as the heeling-lug so that the inclined front end of the spike head finds a correspondingly shaped seat between the rib and spike-lug 13, and it also provides depressions at the sides of the head to permit the insertion of a spike-puller under the head 85 when it is desired to draw the spikes.

In practice, the clips are assembled on their plates on opposite sides of the rail-base, the lugs being passed down through the outer portions of the elongated spike-holes 2 of the plate; the clips are then moved inwardly toward the rail so that their flanges 6 overlie the rail-base and their 90 wings 8 underlie the inner edge of the spike-hole in the plate as shown, the convex lower ends of the lugs entering or crowding the material of the tie sufficiently to seat themselves in place. The flanges 6 and the wings 100 8 interlock the edges of the plates and rail-base together, and when the spikes are driven to place in the ties their heads enter their seats between the ribs 16 and lugs 13 which form front and rear shoulders for 105 the head; the heads act on the inclined surface adjacent the rib to crowd the clips into place, and the lugs 13 heel-up the heads so

that they are not forced outwardly by the lateral thrusts of the rail and the usual throat-cutting of the spikes is obviated.

I claim:

5. 1. A device of the class described comprising a plate having an elongated spike-hole, and a clip having an overhanging flange for a rail-base, a depending lug in the spike-hole of the plate, a wing at the lower end of 10 the lug underlying the inner end of said spike-hole, and a spike-hole in front of the lug in alignment with the spike-hole in the plate.

15. 2. A device of the class described comprising a plate having elongated spike-holes in its opposite sides, and a clip having an overhanging flange for a rail-base, a depending lug in the inner portion of a spike-hole of the plate, an inwardly extending

wing at the lower end of the lug underlying the inner end of said spike-hole, a spike-hole in front of the lug in alignment with the outer end of the spike-hole in the plate, and a seat in the upper face of the clip for the spike-head.

20. 3. A device of the class described comprising a plate having elongated spike-holes in its opposite sides, and a clip having a spike-hole, shoulders at the opposite ends 25 of the spike-hole, an overhanging flange for one side of a rail-base, a depending lug in the inner end of the hole in the plate, an inwardly extending wing at the lower end 30 of the lug underlying the plate, and its upper face concave on each side of its spike-hole and outer shoulder.

35. In testimony whereof I affix my signature.

WARREN M. OSBORN.
